UNITED STATES PATENT OFFICE.

FREDERIK WILLEM BOLK, OF PEKALONGAN, JAVA.

MILL ADAPTED FOR THE CRUSHING OF SUGAR-CANES AND THE LIKE.

1,074,159.

Specification of Letters Patent. Patented Sept. 30, 1913.

Application filed December 7, 1912. Serial No. 735,487.

To all whom it may concern:

Be it known that I, FREDERIK WILLEM BOLK, a subject of the Queen of the Netherlands, residing at Pekalongan, Java, Dutch 5 East Indies, have invented certain new and useful Improvements in Mills Adapted for the Crushing of Sugar-Canes and the like, of which the following is a specification.

This invention relates to mills such as are employed for the crushing of sugar canes and which comprise three rollers—namely, one top roller and two side rollers—the canes or other material to be crushed being passed first between the top roller and the one side 10 roller and afterward between the top roller and the other side roller. Sugar cane mills of this type are usually driven through the top roller shaft which carries a pinion which meshes with pinions keyed on the shafts 15 of the side rollers. The distance between the top roller and either side roller is usually adjusted by giving a horizontal movement to the bearings of that side roller. The movement of adjustment of the side rollers necessitates an adjustment of the dumb- 20 turner and is consequently objectionable. The movements of the top roller for the purpose of adjustment according to my invention, render it undesirable to drive the mill 25 in the usual manner as hereinbefore described. The mill may be driven satisfactorily in any one of several ways. In the accompanying drawings, the driving means illustrated involves the employment of an 30 independent driving shaft which is located at the bottom of the mill and which, by means of pinions, drives the three roller shafts. My invention is not, of course, limited to mills driven in this manner.

40 Referring now to the accompanying drawings:—Figure 1 is a vertical section, on the line A—A of Fig. 2, of a sugar cane mill according to my invention, provided with hydraulic cylinders on the top roller bearings. 45 In this figure the positions of the rollers are indicated by dotted lines. Fig. 2 is, as regards its left-hand portion, an exterior side view of one end of the mill and, as regards its right-hand portion, a vertical section of 50 the mill cheek on the line B—B of Fig. 1, the shafts, rollers and dumbturner being also shown. Fig. 3 is a vertical section on the line C—C of Fig. 2, the shafts being omitted. Fig. 4 is a view corresponding to 55 Fig. 3 and illustrating a mill according to

my invention without hydraulic cylinders. Fig. 5 illustrates an alternative construction, according to my invention, for a mill without hydraulic cylinders.

Referring in the first instance to Figs. 1, 2 and 3, *a* is the mill cheek. There are, as usual, two of these mill cheeks, one at each end of the mill. *b* is the top roller, *c* the side roller at the inlet side of the mill and *d* the side roller at the discharge side of the mill. *e*, *f*, and *g* are respectively the shafts of the three rollers and *h* is the driving shaft. The bearing for the top roller shaft *e* consists of a frame *k* and a bush *m*, the latter being situated within wings or upward extensions *n*, *n* of the frame *k*. A plate *p* is located at the top of the wings *n* and rests thereon. The position of the bearing can be positively regulated as regards height by means of lower wedges *q*, *q*, and upper 70 wedges *r*, *r*, all of which are actuated by rods *s*, *s*. For lateral adjustment of the bearing, wedges *t*, *t* are provided which bear on the one hand against the mill cheek and on the other hand against inclined surfaces 75 formed on ribs *u* which are provided on the wings *n*. The wedges *t*, *t* are moved by means of threaded rods *v*, *v*, these rods being locked in position by means of nuts *w*, *w*, which bear against the top of the cap *y* which extends across the top of the mill 80 cheek. This cap *y* of each cheek is held down to the cheek, and the cheek held down to the bedplate *z*, by means of bolts *x*, *x*. The shaft may rest directly on the frame *k* 90 as shown in the drawings, or a lower bush or liner may be provided in the hollow of the frame. 2, 2, are the bearings for the side rollers. These bearings may consist of solid bushes, as illustrated, which may be 95 fixed within the mill cheek without any means of adjustment, as, according to my invention, the distances between the top roller and the two side rollers are adjusted by moving the top roller bearing. 3 is the bearing for a bottom driving shaft.

When it is desired to increase the distances between the top roller and both side rollers, the wedges *r*, *r*, and *q*, *q*, are moved so as to raise the frame *k*. When it is desired to increase the distance between the top roller and one side roller and to decrease the distance between the top roller and the other side roller, the wedges *t*, *t*, are actuated so as to give a lateral motion to 105 110

the frame *k*. The gap or clearance between the top roller and one side roller can be increased or diminished without increasing or diminishing the gap between the top roller 5 and the other side roller by simultaneous adjustment of the wedges *r*, *q*, and the wedges *t*, *t*. All these movements can be performed when the mill is working.

The mill illustrated in Figs. 1, 2 and 3 is 10 shown as provided with hydraulic cylinders. The bush *m* rises and falls with the pressure on the top roller and under the control of the hydraulic cylinder *o*, the piston *j* of which presses against the under side of the 15 plate *p*. The bush in its automatic movement is guided by the wings *n*, *n*, of the frame *k* between which it slides. In the mill cheek shown in Fig. 4 there is no hydraulic cylinder. The positive adjustment of the 20 top roller bearing by means of the wedges *g*, *r*, *t* is, however, the same as hereinbefore described. Moreover, when there is no hydraulic cylinder or other elastic device interposed between the top roller bearing and the 25 cap *y*, the construction of top roller bearing shown in Fig. 5 may be adopted. In this case the bearing consists of a lower bush *k'* and an upper bush *m'*; and the wedges *t*, *t* act directly on both bushes.

Having thus described my invention, 30 what I claim as new and desire to secure by Letters Patent is:—

1. In a mill adapted for the crushing of sugar canes and the like and in which a 35 top roller engages with each of two side rollers, in combination, a pair of mill cheeks, a shaft which carries the said top roller, bearings for said shaft in said cheeks, means for positively adjusting the height of said 40 bearings within said cheeks, and means for positively adjusting the lateral position of said bearings within said cheeks.

2. In a mill adapted for the crushing of sugar canes and the like and in which a top 45 roller engages with each of two side rollers, in combination, a pair of mill cheeks, a shaft which carries the said top roller, bearings for said shaft in said cheeks, a set of wedges adapted to be moved horizontally and adapted for positively adjusting the height of said 50 bearings within said cheeks, and an independent set of wedges adapted to be raised and lowered and adapted for positively adjusting the lateral position of said 55 bearings within said cheeks.

3. In a mill adapted for the crushing of sugar canes and the like and in which a top roller engages with each of two side rollers, in combination, a pair of mill cheeks, a shaft 60 which carries the said top roller, bearings for said shaft in said cheeks, means for positively adjusting the height of said bearings within said cheeks, means for positively adjusting the lateral position of said bearings 65 within said cheeks, and means for elastically

controlling the automatic upward movement of said top roller with the pressure exerted on it by the material which is being crushed.

4. In a mill adapted for the crushing of sugar canes and the like and in which a top 70 roller engages with each of two side rollers, in combination, a pair of mill cheeks, a shaft which carries the said top roller, bearings for said shaft in said cheeks, a set of wedges adapted to be moved horizontally and adapted for positively adjusting the height of said 75 bearings within said cheeks, an independent set of wedges adapted to be raised and lowered and adapted for positively adjusting the lateral position of said 80 bearings within said cheeks, and means for elastically controlling the automatic upward movement of said top roller with the pressure exerted on it by the material which is being crushed. 85

5. In a mill adapted for the crushing of sugar canes and the like and in which a top roller engages with each of two side rollers, in combination, a pair of mill cheeks, a shaft which carries the said top roller, bearings for said shaft in said cheeks, means for positively adjusting the height of said bearings within said cheeks, means for positively adjusting the lateral position of said bearings within said cheeks, and hydraulic cylinders 90 adapted to control the automatic upward movement of said top roller with the pressure exerted on it by the material which is being crushed. 95

6. In a mill adapted for the crushing of sugar canes and the like and in which a top 100 roller engages with each of two side rollers, in combination, a pair of mill cheeks, a shaft which carries the said top roller, bearings for said shaft in said cheeks, a set of wedges adapted to be moved horizontally and adapted for positively adjusting the height of said 105 bearings within said cheeks, an independent set of wedges adapted to be raised and lowered and adapted for positively adjusting the lateral position of said 110 bearings within said cheeks, and hydraulic cylinders adapted to control the automatic upward movement of said top roller with the pressure exerted on it by the material which is being crushed. 115

7. In a mill adapted for the crushing of sugar canes and the like and in which a top roller engages with each of two side rollers, in combination, a pair of mill cheeks, a shaft which carries the said top roller, bearings for said shaft in said cheeks, said bearings consisting of a frame provided with upwardly-extending wings and an upper bush located within said wings and above said shaft, means for positively adjusting the height of said frames within said cheeks, and means for positively adjusting the lateral position of said frames within said 125 cheeks. 130

8. In a mill adapted for the crushing of sugar canes and the like and in which a top roller engages with each of two side rollers, in combination, a pair of mill cheeks, a shaft which carries the said top roller, bearings for said shaft in said cheeks, said bearings consisting of a frame provided with upwardly-extending wings and an upper bush located within said wings and above said shaft, a set of wedges adapted to be moved horizontally and adapted for positively adjusting the height of said frames within said cheeks, and an independent set of wedges adapted to be raised and lowered and adapted for positively adjusting the lateral position of said frames within said cheeks.

9. In a mill adapted for the crushing of sugar canes and the like and in which a top roller engages with each of two side rollers, in combination, a pair of mill cheeks, a shaft which carries the said top roller, bearings for said shaft in said cheeks, said bearings consisting of a frame provided with upwardly-extending wings and an upper bush located within said wings and above said shaft, a set of wedges adapted to be moved horizontally and adapted for positively adjusting the height of said frames within said cheeks, and an independent set of wedges adapted to be raised and lowered and adapted for positively adjusting the lateral position of said frames within said cheeks, and hydraulic cylinders located within said frames and above said upper bushes and adapted to control the automatic upward movement of said top roller with the pressure exerted on it by the material which is being crushed.

10. In a mill adapted for the crushing of sugar canes and the like and in which a top roller engages with each of two side rollers, in combination, a pair of mill cheeks, a shaft which carries the said top roller, bearings for said shaft in said cheeks, said bearings consisting of a frame provided with upwardly-extending wings and an upper bush located within said wings and above said shaft, a set of wedges adapted to be moved horizontally and adapted for positively adjusting the height of said frames within said cheeks, an independent set of wedges adapted to be raised and lowered and adapted for positively adjusting the lateral position of said frames within said cheeks, and hydraulic cylinders located within said frames and above said upper bushes and adapted to control the automatic upward movement of said top roller with the pressure exerted on it by the material which is being crushed.

movement of said top roller with the pressure exerted on it by the material which is being crushed.

10. In a mill adapted for the crushing of sugar canes and the like and in which a top roller engages with each of two side rollers, in combination, a pair of mill cheeks, a shaft which carries the said top roller, bearings for said shaft in said cheeks, said bearings consisting of a frame provided with upwardly-extending wings and an upper bush located within said wings and above said shaft, a set of wedges adapted to be moved horizontally and adapted for positively adjusting the height of said frames within said cheeks, and an independent set of wedges adapted to be raised and lowered and adapted for positively adjusting the lateral position of said frames within said cheeks, and hydraulic cylinders located within said frames and above said upper bushes and adapted to control the automatic upward movement of said top roller with the pressure exerted on it by the material which is being crushed.

In testimony whereof, I affix my signature in presence of two witnesses.

FREDERIK WILLEM BOLK.
